Primary Examiner — Garth Rademaker*Assistant Examiner* — Salamah Jordan(74) *Attorney, Agent, or Firm* — Diament Patent Law, P.C.; Adam Diament(57) **CLAIM**

The ornamental design for a convertible workout desk, as shown and described.

DESCRIPTION

FIG. 1 is a perspective view of a convertible workout desk, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The evenly dashed broken lines of the disclosure are for environmental purposes only and form no part of the claimed design.

1 Claim, 7 Drawing Sheets(56)
